PHOTOGRAPHIC FILM PROCESSING
APPARATUS

Harry R. Bell, Chicago, Ill.

Application March 7, 1938, Serial No. 194,439

7 Claims. (Cl. 95—93)

My invention relates to photographic film processing or treating apparatus and more particularly to that class wherein a drum is employed upon which the film is secured.

- 8 One of the principal objects of my invention is to provide a photographic film processing apparatus equipped with means for securing the film in a manner whereby the same is subjected to various treating or developing operations.
- 20 Another object of my invention is to provide a device of the above described character equipped with means for excluding light from one side of the film during the treating operations, including means for conserving the solutions during such operations.

A further object of my invention is to provide an apparatus of the above described character having means for automatically taking up any swelling or stretching of the film during the 20 treating operations and thereby prevent overlapping or entanglement of the film.

A still further object of my invention is to provide an apparatus of the above described character operable in a manner to agitate the processing solutions during the treating operations and thereby effect a uniform treatment of the film.

Another important object of my invention is to provide a means of guarding the film during the treating thereof to prevent damage to its base or emulsion and at the same time permit visual inspection over the entire surface of the film.

Other objects, for instance, means of exposing the film to light uniformly over its entire length or any section thereof during the treating operations, means by which the film may be kept from widely varying temperatures during treatment or held in the scope of some desired temperature, means whereby the drum of the apparatus on which the film is contained may be readily detached thereby permitting another drum to be substituted for treating other film, means embracing a deep and continuous film track whereby loading of the film for treatment may be accomplished in the dark without being subjected to harmful light rays, and means provided for the instant change of the film from one solution to another without the necessity of waiting to drain a used tray and refill the same thereby providing for continuous treating operation, will be apparent from the following description, appended claims and annexed drawings.

Referring to the drawings wherein like reference characters designate like parts throughout the several views:

55 Fig. 1 is a side elevation of my invention.

Fig. 2 is a top plan view thereof.

Fig. 3 is a sectional view taken on the line 3—3 of Figure 1.

Fig. 4 is a detail fragmentary side elevation, partly in section, illustrating the drum positioned 5 for rotation within one of the trays.

Fig. 5 is a detail perspective view of a clip used in securing the end of a film to the drum.

Fig. 6 is a detail perspective view of an anchoring member which coats with a resilient member 10 and clip to secure the end of a film to the drum.

In practicing my invention there is provided an elongated base or bed 5 of substantially rectangular configuration comprising side members 6 secured to each other in spaced relation by transverse members 7. Supported on each pair of the transverse members 7 is a tray 8, said trays adapted to contain a suitable developing or treating solution for a film hereinafter set forth. 20 Intermediate of the trays 8, the side members 6 have secured thereto upwardly extending brackets 9 in which are journaled the end sections of a transversely extending shaft 10.

Mounted on the ends of the shaft 10 adjacent 25 the brackets 9 are upwardly extending support members 11, the upper ends of which are slotted as at 12 to receive therein a hollow driven shaft 13 on which is mounted a drum 14 adapted to receive on the outer periphery thereof photographic film. The lower ends of the support members are secured to the shaft 10 by means of pins 15 extending through the ends of said shaft 10 as clearly illustrated in Figure 3 of the drawings. The lower ends of the pins 15 are apertured to receive the ends of a pair of coil springs 16. The opposite ends of said coil springs are connected to adjustable rods 17 slidably connected to the bed 5 by means of eye members 18 adjacent the ends of said bed. Knurled nuts 19 40 are employed on the ends of said rods for engagement with eye members whereby said rods are adjustable to vary the tension of the springs 16.

The drum 14 is fashioned on the outer periphery thereof with a radially and spirally extending flange 20 forming a plurality of channels 21 for receiving therein a length of photographic film 22. Each end of said film is folded to form a loop for retaining therethrough a resilient member 23 and said loop is secured in folded position about said resilient member by means of a spring clip 24 as clearly illustrated in Figure 5. The elastic member 23 adjacent the outer end of the drum is secured to the drum by means 55

of an inflected section 25 formed on the drum. The elastic member 23 secured to the opposite end of the film is secured to a hook 26 of an anchoring member 27, said member being provided with resilient sides for engagement with the side walls of the respective channel in which the aforesaid end of the film terminates. Due to the resilient member 23 the length of film extending about the drum is maintained in tensioned condition, one side thereof engaging the outer periphery of the drum thereby excluding light from said side. The sides of the drum 14 comprise a circumferentially extending flange having inwardly extending spokes mounted on the shaft 13 and said flange forms a reservoir for receiving liquid introduced therein through the hollow shaft 13 and outlet ports formed therein. This liquid is of such a temperature that the film may be maintained at a desired temperature during the processing thereof.

Mounted on the shaft 10 is a cone pulley having belt sections 28 and 29. The section 29 is connected to a pulley 30 fixed on the shaft 13 by means of a drive belt 31 and the section 28 is connected to a drive pulley 31a on a motor drive shaft 32 by means of a belt 33. A suitable electric motor 34 having the drive shaft 32 is mounted adjacent one of the side members 6 and serves to rotate the drum 14 through the connected chain or mechanism heretofore described. On each side of the brackets 9 are eccentrically mounted stop blocks 35 by means of screws 36, said stop blocks being adjustable about said screws. Subjacent the drum 14 and having ends connected to the support members 11, is a drip shield 37 whereby to direct liquid dripping from the drum into the tray in which the drum is positioned for operation. It is to be understood that by disconnecting the drive belt 31 from the pulley 30, the shaft 13 carrying the drum 14 may be disengaged from the supports 11 and a drum for accommodating film of a different width attached for operation thereto.

When the supports 11 are positioned vertically between the trays 8, the springs 16 coact with each other to balance the drum in said position and said drum may be rotated for inspection of the film or other purpose.

Movement of the drum or supports towards either of the trays 8 will permit the drum to be maintained in rotating position within said trays by means of the pins 15 engaging the stop members 35.

As heretofore stated, the stop members 35 may be adjusted about the screws 6 to adjust the position of the drum relative to the inner periphery of the trays. In this position, the weight of the drum is sufficient to overcome the resiliency of one of the springs, the other spring coacting with the supports to maintain the drum in the desired tray. When the drum is positioned for rotation within the trays, the same is rotated in the same manner as described in the vertical or neutral position.

From the foregoing it will be apparent that I have provided a simple and efficient apparatus upon which photographic film may be secured and subjected to the various developing operations.

70 What I claim is:

1. A device of the character described, comprising, a bed, support members pivoted to said bed, a drum having a drive shaft journaled in said members, said drum adapted to receive thereon photographic film, spaced trays subja-

cent said drum, and means carried by said support members and connected to said bed on each side of said members whereby to effect positioning of said drum between said trays and to permit positioning of said drum in either of said trays.

2. A device of the character described, comprising, a bed, support members pivoted to said bed, a drum having a drive shaft journaled in said members, said drum adapted to receive thereon photographic film, spaced trays subjacent said drum, means carried by said support members and connected to said bed on each side of said members whereby to effect positioning of said drum between said trays and to permit positioning of said drum in either of said trays, and a source of power connected to said drum whereby to rotate the same in the said positions.

3. A device of the character described, comprising, a bed, support members pivoted to said bed, a drum having a drive shaft journaled in said members, said drum adapted to receive thereon photographic film, means for attaching said film to said drum, spaced trays subjacent said drum, and means carried by said support members and connected to said bed on each side of said members whereby to effect positioning of said drum between said trays and to permit positioning of said drum in either of said trays.

4. A device of the character described, comprising, a bed, brackets secured to said bed, support members pivoted to said brackets, a drum detachably mounted between said support members, said drum formed with a spiral channel on the outer circumference thereof, means in said channel for securing a length of film therein, spaced trays subjacent said drum and supported on said bed, arms carried by said support members, stop members adjustably mounted on said brackets coacting with said arms for limiting the movement of said support members, springs carried by said arms and adjustably connected to said bed on each side of said brackets whereby to effect positioning of said drum between said trays and to permit the positioning of said drum in either of said trays, a source of power mounted adjacent said bed, and means connecting said source of power to said drum whereby to rotate said drum in any of said positions.

5. A device of the character described, comprising, a bed, support members pivoted to said bed, a drum having a drive shaft journaled in said members, said members adapted to have secured thereon photographic film, resilient means carried by said drum for attaching said film thereto and maintaining the film in a tensioned condition about said drum, spaced trays adjacent said drum, and means carried by said support members and connected to said bed on each side of said members whereby to effect positioning of said drum between said trays and to permit ready positioning of said drum from one tray to another.

6. A device of the character described, comprising, a bed, support members pivoted to said bed, a drum having a drive shaft journaled in said members, said drum adapted to receive thereon photographic film, spaced trays subjacent said drum, and means carried by said support members and connected to said bed on each side of said members whereby to effect positioning of said drum between said trays and to permit positioning of said drum in either of said trays, said drum fashioned with circumfer-

entially extending flanges forming a well within said drum whereby to receive liquid therein for maintaining said film at a desired temperature.

5 7. A device of the character described, comprising, a bed, support members pivoted to said bed, a drum having a drive shaft journaled in said members, said drum adapted to receive thereon photographic film, spaced trays subjacent said drum, means carried by said support member

and connected to said bed on each side of said member whereby to effect positioning of said drum between said trays and to permit positioning of said drum in either of said trays, and a drip shield subjacent said drum for directing solution from said film into one of said trays when said drum is positioned between said trays. 5
